JOHN F. MEADER, OF NEW YORK, N. Y.

GAS COMBUSTION APPARATUS

Application filed December 6, 1927. Serial No. 238,146.

This invention relates to gas combustion apparatus, and comprises a novel apparatus for the combustion of fuel gas, being herein illustratively shown as employed in a gas fired furnace, such for example as may be used for house heating purposes, for heating or vaporizing water, or similar uses. For residence heating the invention may be used with steam, hot water, vapor or air systems.

10 The general object of the present invention is to afford a gas combustion apparatus or furnace possessing high efficiency, convenience of operation and control, simplicity of structure and rugged durability. A particular object is to adapt existing coal furnaces to gas firing, with ease of installation. Another object is economy, both of labor and fuel, with possibility of thermostatic control and safety of operation. A further object 15 is to afford a system of gas heating which will be operative with ordinary municipal service gas pressures, without requiring high pressure of gas. A further object is to improve the heating efficiency of gas combustion by practically applying the generated heat thereof initially to a mass of radiant or incandescent bodies, the heat being then communicated both by convection and radiation to the boiler or other device to be heated.

20 Other and further objects and advantages of the invention will be explained in the hereinafter following description of an illustrative embodiment thereof or will be understood to those conversant with the subject. 25 To the attainment of the said objects and advantages the present invention consists in the novel gas fired furnace or apparatus, and the novel features of operation, combination, arrangement and structure herein illustrated or described.

In the accompanying drawings Fig. 1 is a general elevation, partly in central section, and partly diagrammatic, of a gas combustion apparatus illustrating the principles of the present invention.

Fig. 2 is a section taken on the line 2—2.

Fig. 3 shows a modification.

Referring to the drawings there is shown a furnace 10, the fire box of which may be of double construction and resting upon a base

section 11. With the furnace is shown embodied a boiler, represented by the portions or legs 12 at the periphery and 13 at the center exposed to the incandescent heat of the radiant bed to be described. Between the 55 water legs are flues 14 for the outgoing gases and at the front of the furnace is shown the usual fire door 15 giving access to the fire box or combustion chamber.

Within the base section and resting on the 60 bottom or floor are shown the gas connections including a chamber or gas pot 16 from which extends an uptake 17, the height of which will be predetermined, or adjusted, to bring the bed of radiants in the proper relation below the water surfaces of the boiler. At the top of the uptake 17 is shown a threaded ring 18 having vertical posts 19, three of these being indicated, constituting a tripod. Upon this tripod rests a preferably round 65 plate or disk 20 which acts as a spreader for distributing laterally the ascending gas and air mixture. The underside of the plate 20 may have recesses receiving the top ends of the three posts 19. On top of the plate 20 70 and suitably attached or positioned thereon is shown a larger plate or table 21 which is built up of two or more sections to permit their insertion through the fire door and assemblage within the furnace. The fire table 75 21 is preferably unbroken and constitutes a support for the radiant bed, but its periphery is smaller than the furnace shell so that a peripheral passage or passages 24 are shown leading upwardly between the table and the shell. Above the fire table and between it and the water leg 13 is a space which may be considered the combustion chamber 25.

Resting upon the table 21 and occupying 80 a portion of the combustion chamber is shown a radiant bed composed preferably of a loose assemblage of radiant elements 26. These may be of various shapes, but are preferably briquettes of double pyramid shape and composed of ceramic or refractory material which is readily brought to an incandescent condition. It will be observed that the bed of radiants 26 is arranged to face the boiler 85 both at its upper center portion and at its 100

edges, the bed preferably being rounded over substantially as illustrated.

Gas may be supplied to feed the uptake 17 by a gas main 28. In this main is provided a gas cock 29 which according to this invention is preferably thermostatically controlled so as to increase or decrease the supply of gas according to the heating needs. Inwards of the cock 29 is a delivery pipe 30 having at its extremity a sharp edged orifice disk 31 containing either seven or other plural number of orifices 32 or a single equivalent orifice 32^a as in Fig. 3. The gas orifices 32 or 32^a deliver into the tapered portion 34 of a Venturi tube so as to create an induced action carrying the gas and indrawn air through and out by the flaring portion 35 of the Venturi tube. The mouth of the tapered portion 34 of the tube is preferably not freely open but is partially closed by fixed damper portions 37 cooperating with rotary damper portions 38 so as to regulate the amount of air in relation to the rate of gas flow. The Venturi tube 34-35 is shown surrounded by a pipe or housing 40 which leads directly to the gas pot 16, so that the gas-air mixture is conducted to the uptake 17 and thus delivered below the spreader plate 20 from which it passes outwardly and through the passages 24 to the bed of radiants 26.

In its preferred form this invention embodies, in addition to the gas connections already described another set of gas connections as follows. A preferably smaller gas supply pipe 42 is shown provided with a cock 43 delivering through pipe 44 and orifice to the damper controlled tapered portion 45 of a Venturi tube, the flaring portion 46 of which is enclosed within a pipe 48 which enters the gas pot 16 and is provided with an elbow connected to an uptake 49 preferably located concentrically within the uptake 17, the upper end 50 of the interior pipe discharging into what may be termed the distributing space 51 below the center of the spreader plate 20. Instead of carrying the primary gas pipe into the fire pot through a packed connection as shown I am employing a specially designed fire pot, which may be cast with an upper opening for the larger secondary gas pipe and fitting and a smaller lower opening to which the primary gas pipe may be exteriorly fitted, and with a pipe cast interiorly in the gas pot and extending inwardly and curving upwardly, terminating in a threaded end to which the small interior uptake 49 may be fitted, thus simplifying the manner of assembling the apparatus.

In operation it will be understood that the interior or smaller gas connection system is intended to be in constant operation so as to maintain the radiants in a radiating state. This primary system is supplemented by the variable secondary system by which the total amount of gas-air mixture and heating effect

are automatically regulated. Each system supplies substantially the same gas-air mixture to the distributing chamber 51 from which the mixture flows radially outward and thence upwardly to the passages 24. An action is created in the combustion chamber 25 which is found to draw the gases inwardly through the heart of the bed of radiants so that in practice the radiants become incandescent from center to periphery. By this arrangement a very large portion of the available heat is expended in maintaining the radiants in their incandescent condition and these effectually radiate the heat to the boiler, while the outgoing hot gases carry further heat to the boiler by convection. The combination gives maximum efficiency.

The combustion commences at the burner head, in the distributing space, the flames being deflected beneath the spreader and the metallic fire plate, and heating the plate from below, this becoming radiantly hot, so that the plate as well as the radiants radiates heat to portions of the boiler. The fire plate is in the nature of a circular baffle, causing the combustion flames to travel a tortuous route, for the best extraction of thermal units. The hot gases travel in direct contact with the boiler portions below the fire plate or baffle.

The orifice arrangement at the gas supply is effective in drawing large quantities of air into the furnace, but the regulation is to be such as to give the usual excess of gas, and thus prevent explosion and flashing back.

There have thus been described a gas combustion method and apparatus embodying the principles of this invention; but since many matters of operation, combination, arrangement and structure may be variously modified without departing from the principles it is not intended to limit the invention to such matters except so far as set forth in the appended claims.

What is claimed is:

1. A gas-fired furnace having firebox walls enclosing the combustion space, a substantially imperforate metallic table mounted horizontally in the combustion space at such height as to leave chambers of substantial depth both below and above the table, said table being constructed in relation to the firebox walls to leave an upflow passage substantially peripherally around the table, a gas-air conduit arranged centrally in the lower chamber to deliver flame upwardly to impinge directly against the central portion of the under side of the table to maintain the central portion of the table at high temperature, and a firebed of refractory radiant bodies piled upon said table in loosely assembled relation to receive heat and become incandescent and radiate to the heat absorbing surfaces of the upper chamber.

2. A gas-fired furnace having heat absorbing metallic firebox walls enclosing the com-

bustion space, a substantially imperforate metallic table suspended in the combustion space at such height as to leave chambers of substantial depth both below and above the table, said table being constructed in relation to the firebox walls to leave an upflow passage substantially peripherally around the table, a gas burner arranged in the lower chamber to deliver flame upwardly to impinge against the middle portion of the under side of the table to maintain the same at high temperature, and a firebed of refractory radiant bodies carried upon said table arranged higher in the middle to constitute a convex firebed radiating to the walls of the upper chamber.

3. A gas-fired furnace having metallic firebox walls enclosing the combustion space, a substantially imperforate metallic plate suspended transversely in the combustion space at such height as to leave chambers of substantial depth both below and above the plate, said plate being constructed in relation to the firebox walls to leave an upflow passage substantially peripherally around the plate, a gas-air conduit and burner arranged in the lower chamber to deliver flame upwardly to impinge against the central portion of the under side of the plate to maintain a central area of high temperature, and a firebed of piled refractory radiant bodies carried upon said plate in loosely assembled relation and at the periphery overhanging such upflow passage and confined by the firebox walls.

35 4. A gas-fired furnace having firebox walls enclosing the combustion space, a substantially imperforate metallic table mounted in the combustion space at such height as to leave chambers of substantial depth both below and above the table, said table being constructed in relation to the firebox walls to leave an upflow passage substantially peripherally around the table, a gas-air burner comprising main and auxiliary conduits both arranged in the lower chamber to deliver flame upwardly to impinge directly against the central portion of the under side of the table and having means to put one or both thereof into or out of operation, and a system of refractory radiant bodies carried upon said table in loosely assembled relation to constitute a firebed radiating to the heat absorbing surfaces of the upper chamber.

55 In testimony whereof, I have affixed my signature hereto.

JOHN F. MEADER.
